UNITED STATES PATENT OFFICE.

EDWIN G. STAUME, OF MINNEAPOLIS, MINNESOTA.

ATTACHMENT FOR PAPER-SLOTTING MACHINES.

1,418,844.

Specification of Letters Patent. Patented June 6, 1922.

Application filed December 27, 1920. Serial No. 423,530.

To all whom it may concern:

Be it known that I, EDWIN G. STAUME, a citizen of the United States, resident of Minneapolis, county of Hennepin, State of Minnesota, have invented certain new and useful Improvements in Attachments for Paper-Slotting Machines, of which the following is a specification.

My invention relates to machines for slotting paper blanks preparatory to folding and the object of the invention is to provide an attachment which will cause the strips or boxes of paper cut out of the blank by the operation of the knives to become readily separated from the blank soon after the slot is formed.

A further object is to provide a means to this end which will not in any way interfere with the cleaning finger used in connection with the slotting rolls and knives for cleaning the waste paper out of the grooves in the rolls.

The invention consists generally in various constructions and combinations, all as hereinafter described and particularly pointed out in the claims.

In the accompanying drawings forming part of this specification,

Figure 1 is a vertical sectional view through a paper slotting machine embodying my invention,

Figure 2 is a detail sectional view, showing the operation of slotting the paper,

Figure 3 is a plan view of one of the slotting rolls,

Figure 4 is a sectional view on the line 4-4, of Figure 3,

Figure 5 is a detail view, showing the blanks passing over the roll.

In the drawing, 2 represents the frame of the machine, having the usual hopper 3 and 4 and 5 are the upper and lower cutting rolls between which the blanks are delivered from the bed or feed 6. These rolls are provided with co-operating cutting knives 7 and 8 and a groove 9 is provided in the surface of the lower roll into which the tongue 10 cut from the blank 11 is adapted to enter. A cleaning finger 12 is mounted at 12^a and is adapted to sweep through the groove 9 and remove any of the loose tongues which may have gathered or accumulated therein. The width of the groove is such that a considerable portion of the material will unite the tongue with the blank and this area of connection is so large that in machines as

usually constructed, the tongue will not become readily separated from the blank but frequently will pass through the machine still clinging thereto. Some may become torn from the blank and lodge in the groove in the roll to be separated therefrom by the cleaning finger, but many of them will pass on with the blank and have to be removed by hand at some later period.

To eliminate this objection of having the tongue cling to the blank, I mount a plug 13 preferably of steel, within a socket 14 in the groove and provide in said plug a narrow slit 15 that is just wide enough to allow the passage of the cleaning finger 12, the edges of the plug on each side of the slot forming knives for severing the tongue transversely until the one part connecting it with the blank is a narrow section of the material corresponding in width to the slot and usually is insufficient to hold the tongue and the material together, so that most of the tongues will become separated from the blank and drop down outside of the machine or be collected by some suitable means without any attention on the part of the operator. The roll beneath the socket 14 has an opening 16 through which access may be had to the plug for the purpose of driving it out of the socket in the wall when it becomes worn or needs replacing.

In the operation of the device, the blanks are fed to the machine and cut in the usual way and the edge of the plug on each side of the slot therein will cut transversely through the tongue at the point where it joins the blank until it is almost severed, the connection corresponding to the width of the slot in the plug. Through this slot in the plug the cleaning finger will pass in the revolution of the roll and dislodge any of the cut-out material which may be clinging in the grooves in the rolls, while the tongues that have been cut from the blanks, being nearly severed, in passing the plug will usually drop off before the blank has passed out of the machine.

I thus practically insure the removal of the waste tongues from the blanks without in any way interfering with the operation of the cleaning finger.

I claim as my invention:

1. The combination, with a blank slotting roll having a peripheral groove therein and a cleaning finger operating in said groove, of a plug mounted in said roll and having a

slot therein of sufficient width to allow the passage of said cleaning finger and of less width than the groove in said roll.

2. The combination, with paper cutting rolls having co-operating knives and grooves therein and a cleaning finger operating in the grooved roll and means mounted in the periphery of the roll for partially severing the tongue from the blank and said means having a slot therein to allow the passage of the cleaning finger.

3. The combination, with a roll having a peripheral groove therein and a socket intersecting said groove, of a plug fitting said socket and having a slot therein of less width than the width of said groove and cutting edges upon each side of said slot.

4. The combination, with a roll having a peripheral groove and a radial socket intersecting said groove, a plug seated in said

socket, said roll having an opening exposing the inner end of said plug for driving it out of said socket, said plug having a comparatively narrow slot therein and cutting edges upon opposite sides of said slot, and a cleaning device operating in said groove and slot.

5. The combination, with a roll having a peripheral groove therein and means for cutting a slot in paper stock, of means mounted to project into said groove and partially sever the waste strip of paper left on the blank by the cutting of said slot, said means having a gap therein and a groove cleaning finger mounted to pass through said gap.

In witness whereof, I have hereunto set my hand this 20th day of December, 1920.

EDWIN G. STAUDE.
